UNITED STATES PATENT OFFICE

2,535,270

DEVICE TO PREVENT BREAKAGE OF
POLES AND WIRES

Vernon Carroll Davis, Holabird, S. Dak.

Substituted for abandoned application Serial No.
543,475, June 10, 1931. This application March
5, 1948, Serial No. 13,118

4 Claims. (Cl. 174—158)

1.

My invention relates to the arts of telegraphy, telephony, and electrical power transmission, and it particularly has reference to the stringing of line or circuit wires on poles.

The general practice at present is to provide poles with cross arms carrying insulator pins, on which the insulators are screwed. The line wires are anchored or tied to these insulators and strung from pole to pole.

In storms, especially sleet and ice storms, and storms of high wind velocity, the wires get mechanically overloaded and frequently break, or the poles are broken off with much damage.

My invention therefore has for an object to provide a means of mounting the line wires on the poles in such a way that on the line wires becoming mechanically loaded beyond a predetermined weight or degree, the insulator with the line wire attached will become automatically released from the pole so that the insulator and line wire will be free to fall to the ground without breaking either the pole or the line wire.

Generically, the invention resides in providing an insulator carrying arm, to the insulator of which the line wire is anchored as usual and which arm is releasably mounted in a suitable block which is securely fastened on the cross arm of the pole; the arrangement is such that upon excess weight or strain being put on the line wire it will cause the arm to release itself from the block and fall free of the same.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawing, in which:

Figure 1 is an elevation of the top part of a pole equipped with my invention.

Figure 2 is an enlarged vertical section of one of the wire supporting units, the parts being in the normal position in full lines and in an abnormal position in dotted lines.

In the drawing, in which like numerals of reference indicate like parts in all the figures, 1 represents the pole whose cross arms 2 are braced at 3 in the usual manner.

4 is a mounting block which has a shank 5 bolted at 6 to the cross arm and which is provided with a chamber 7 entering from the bottom.

8 is a transverse threaded bore intersecting the

2.

chamber 7 and in which is located a latch 11, screw plug 9 and spring 10, the latch having a shank 12 to receive the spring.

13 is another transversely threaded bore intersecting the chamber 7. This pole carries a presser piston 15, pressed by a spring 14, into which the shank 16 of the presser piston 15 projects. The compression of the spring 14 is regulated by a suitable adjusting screw plug 17.

10 The insulator arm 20 has a threaded pin portion 21 for the insulator 22 to which the line wire 24 is secured in the usual way. The arm 20 has a shank 18 that projects up into the chamber 7 and has a bevelled heel 19 to engage the latch 11 on which it hangs. The shank 18 also engages, at 23, the block 4 as the fulcrum of a lever, so that when excess weight is applied to the insulator carrying end of the arm it will be caused to rock on the fulcrum 23, thereby disengaging the end 19 from the latch 11 and dropping out of the chamber 7. The tendency of the arm 20 to rock on the fulcrum 23 is resisted by the presser piston 15, the degree of resistance being adjustable by virtue of the screw plug 17. By moving the plug in or out the compression may be increased or diminished as desired. Having once set the tension of the spring 14 it will take a predetermined weight on the insulator end of the arm 20 to force the piston back and enable the end 19 of the shank 18 to clear the latch 11 so that the insulator carrying arm 20 can fall out of the block 4.

In restoring the parts to their assembled position it is only necessary to push 18 up into the chamber 7 where it will force in the latch 11 until 19 has cleared it when the latch 11 will be projected under the end 19 to hold it as before.

This application is a substitute for application Serial No. 543,475, filed June 10, 1931, now abandoned.

From the foregoing description, taken in connection with the accompanying drawing, it is thought the complete construction, operation, and advantages of my invention will be clear to those skilled in the art.

What I claim is:

1. In a device of the character described, a fixed block to be mounted on the cross arm of a pole, an insulator carrying lever arm, and means 50 releasably mounting said arm in said block for release upon overloading the insulator carrying part of the arm, said block having a socket into which one end of said arm projects, the other end of the arm carrying the insulator, yieldable means engaging that end of said arm which is

within the socket to hold the same therein, said arm pivotally engaging a portion of said block to function as a lever to rock the end of said lever away from said yieldable means when the insulator carrying end thereof is mechanically overloaded to release the lever from the holding means.

2. In a device of the character described, a fixed block to be mounted on the cross arm of a pole, an insulator carrying lever arm, and means detachably mounting said arm in said block for release upon overloading the insulator carrying part of the arm, said block having a socket into which one end of said arm projects, the other end of the arm carrying the insulator, means engaging that end of said arm which is within the socket to hold the same therein, said arm functioning as a lever to rock when the insulator carrying end thereof is mechanically overloaded to release itself from the holding means, and adjustable resistance means engaging said arm and tending to prevent its release below a predetermined load.

3. In a device of the character described, a fixed block to be mounted on the cross arm of a pole, an insulator carrying lever arm, and means detachably mounting said arm in said block for release upon overloading the insulator carrying part of the arm, said block having a socket into which one end of said arm projects, the other end of the arm carrying the insulator, means engaging that end of said arm which is within the socket to hold the same therein, said arm functioning as a lever to rock when the insulator carrying end thereof is mechanically overloaded to release itself from the holding means, and adjustable resistance means engaging said arm and

tending to prevent its release below a predetermined load, said adjustable resistance means comprising a presser piston, a piston pressing spring and means for adjusting the tension of said spring.

4. In a device of the character described, a fixed block to be mounted on the cross arm of a pole, an insulator carrying lever arm, and means detachably mounting said arm in said
- 10 block for release upon overloading the insulator carrying part of the arm, said block having a socket into which one end of said arm projects, the other end of the arm carrying the insulator, a latch yieldably engaging that end of said arm
- 15 which is within the socket to hold the same therein, said arm functioning as a lever to rock when the insulator carrying end thereof is mechanically overloaded to release itself from the holding means, and resistance means engaging said
- 20 arm and tending to prevent its release below a predetermined load.
